NOVEL PROCESS FOR THE PREPARATION OF
 $9\beta,11\beta$ -OXIDO DERIVATIVES OF STEROID
COMPOUNDS

20 Claims. (Cl. 260—239.55)

This invention is concerned with a novel process for the preparation of $9\beta,11\beta$ -epoxy steroids. More particularly, this invention relates to an improved process for the preparation of $9\beta,11\beta$ -epoxy steroids by the treatment of the corresponding 9α -bromo- 11β -hydroxy steroid with potassium fluoride in a substantially neutral medium.

It has long been known that such 9-halo- 11β -hydroxy steroids as 9α -fluorocortisone, 9α -fluorohydrocortisone, 9α -fluoroprednisone and 9α -fluoroprednisolone and the 16α - and 16β -methyl and 21-ester derivatives thereof display anti-inflammatory activity far greater than that afforded by the corresponding 9-des-halo compounds. Heretofore, preparation of these and other therapeutically active 9-halo- 11β -hydroxy steroids has involved the conversion of 9α -bromo- 11β -hydroxy intermediates to the corresponding $9\beta,11\beta$ -epoxide by treatment of the bromohydrin 21-esters with alkalis, such as sodium acetate in acetone, or alkali bases, such as sodium hydroxide and sodium methoxide in methanol. Conversion of the epoxide to the desired halo-hydrin is subsequently accomplished with hydrogen halide. Epoxide formation by the conventional process, however, has not proved entirely satisfactory since treating the bromohydrin at reflux in an alkaline medium often results in undesired side reactions such as, for example, hydrolysis of ester groupings at other positions in the steroid nucleus, D-homoannulation of the D-ring and rearrangement and degradation of the cortical side-chain.

By employing the process of the instant invention, the possibility of such undesired side reactions is substantially eliminated. Accordingly, it is the object of this invention to provide an improved process for the conversion of a 9α -bromo- 11β -hydroxy steroid into the corresponding $9\beta,11\beta$ -epoxide. It is a further object of this invention to provide an improved method for the preparation of $9\beta,11\beta$ -epoxy steroids from the corresponding 9α -bromo- 11β -hydroxy intermediates wherein the bromohydrin is treated with potassium fluoride in a substantially neutral medium under conditions which result in the formation of the epoxide in high and relatively pure yield.

The instant invention is based upon the discovery that by treating a 9α -bromo- 11β -hydroxy steroid such as, for example, 16α -methyl- 9α -bromo-1,4-pregnadiene- $11\beta,17\alpha$, 21-triol-3,20-dione 21-acetate with potassium fluoride in either a S,S-disubstituted sulfoxide or a N,N-disubstituted amide, the corresponding $9\beta,11\beta$ -epoxide (i.e., 16α -methyl- $9\beta,11\beta$ -oxido-1,4-pregnadiene- $17\alpha,21$ -diol-3,20-dione 21-acetate) is formed in high and relatively pure yield.

By the term, S,S-disubstituted sulfoxides is meant S,S-dislower alkyl sulfoxides, including straight and branched chain isomers, such as, for example, dimethylsulfoxide wherein the lower alkyl moiety contains from 1 to 4 carbon atoms and cyclo-lower alkyl sulfoxides such as, for example, tetra-hydrothiophene sulfoxide wherein the cyclo-lower alkyl moiety contains from 4 to 5 carbon atoms. By the term, N,N-disubstituted amide, is meant N,N-di-lower alkyl formamides and N,N-di-lower alkyl acetamides, including straight and branched chain isomers, such as, for example, dimethylformamide or diethylacetamide wherein the lower alkyl moiety contains from 1 to 2 carbon atoms; N-lower alkyl- α -pyrrolidones, including straight and branched chain isomers, such as, for example, N-methyl- α -pyrrolidone, wherein the lower alkyl moiety

contains from 1 to 2 carbon atoms; and N-lower alkyl- α -piperidones, including straight and branched chain isomers, such as, for example, N-ethyl- α -pyrrolidone, wherein the lower alkyl moiety contains from 1 to 2 carbon atoms.

The quantity of potassium fluoride used in the process of this invention must be at least two moles per mole of steroid, the preferred ratio being about four moles of potassium fluoride to one mole of steroid. Because of the limited solubility of potassium fluoride in the solvents of this process, the volume of solvent per mole of potassium fluoride, though subject to variation with the reaction temperature, is a critical factor. The minimum amount of solvent which can be used per mole of steroid is about five liters; the preferred ratio being about ten liters of solvent per mole of steroid. The temperature range over which the reaction may be carried out will depend upon the solvent employed. In general, the reaction temperature may vary from a minimum of about 25° C. up to the reflux temperature of the solvent. It is desirable, however, to keep the reaction temperature below 100° C.; the preferred temperature range being from 75 to 90° C.

In general, the preferred method of carrying out the process of this invention is to heat a mixture of one mole of 9α -bromo- 11β -hydroxy steroid and four moles of potassium fluoride in ten liters of solvent (e.g., dimethylsulfoxide or dimethylformamide) at about 90° C. for approximately 8 hours. The reaction mixture is then poured into ice water and the crude epoxide is recovered by filtration. Purification is effected by recrystallization in the usual manner from such organic solvents and solvent mixtures such as acetone, acetone-hexane, ethyl acetate-hexane, etc.

If, in the process described above, only five liters of solvent are used for the same quantity of steroid, very little epoxide will be formed after heating at 90° C. for only 8 hours. Under these conditions, the reaction may require about 72 hours to go to completion. As a further example, one mole of steroid and 2 moles of potassium fluoride in 30 liters of solvent at room temperature takes about 48 hours to go to completion. The optimum reaction time which varies from 4 to 72 hours depends upon the temperature, the relative concentration of steroid, amount of potassium fluoride and solvent.

The process of the instant invention is one of general applicability and may be used to convert any 9α -bromo- 11β -hydroxy steroid into the corresponding $9\beta,11\beta$ -epoxy compound. The 9α -bromo- 11β -hydroxy starting materials and the methods for their preparation are, of course, well known in the art.

The following examples are set forth as further and more particular illustrations of the process of the instant invention. No limitation, however, is intended except as defined in the appended claims.

Example 1

Mix 15 g. of 16α -methyl- 9α -bromo-1,4-pregnadiene- $11\beta,17\alpha,21$ -triol-3,20-dione 21-acetate, 300 ml. of dimethylsulfoxide and 6.6 g. of potassium fluoride. Stir the reaction mixture at 85-90° C. for 7-8 hours and pour into about 1.5 l. of ice water with continued stirring. Recover the crude 16α -methyl- $9\beta,11\beta$ -oxido-1,4-pregnadiene- $17\alpha,21$ -diol-3,20-dione, 21-acetate by filtration and purify by recrystallization from ethyl acetate-hexane.

Example 2

Mix 2.5 g. of 16α -methyl- 9α -bromo-1,4-pregnadiene- $11\beta,17\alpha,21$ -triol-3,20-dione 21-acetate, 1.1 g. of potassium fluoride and 100 ml. of dimethylformamide. Stir at 90° C. for about 16 hours. Recover and purify the epoxide as in Example 1.

Example 3

Stir a mixture of 2.5 g. of 16α -methyl-9 α -bromo-1,4-pregnadiene-11 β ,17 α ,21-triol-3,20-dione 21-acetate, 0.55 g. of potassium fluoride and 150 ml. of dimethylsulfoxide at 25° C. for about 48 hours. Recover and purify the epoxide as in Example 1.

Example 4

Heat to 85-90° C. with stirring a mixture of 15 g. of 16α -methyl-9 α -bromo-1,4-pregnadiene-11 β ,17 α ,21-triol-3,20-dione 21-acetate, 300 ml. of dimethylacetamide and 6.6 g. of potassium fluoride. Continue stirring at this temperature for 7-8 hours. Recover and purify the epoxide as in Example 1.

Example 5

Mix 4.85 g. of 9 α -bromo-4-pregnene-11 β ,17 α ,21-triol-3,20-dione 21-acetate, 2.32 g. of potassium fluoride and 100 ml. of dimethylsulfoxide. Heat to about 90° C. and stir for 7-8 hours. Pour the reaction mixture into approximately 1.5 l. of ice water with continued stirring and separate the crude $9\beta,11\beta$ -oxido-4-pregnene-17 α ,21-diol-3,20-dione 21-acetate by filtration. Purify by recrystallization from acetone.

Example 6

Employ the process of Example 5, substituting for the dimethylsulfoxide solvent 100 ml. of diethylsulfoxide, to prepare $9\beta,11\beta$ -oxido-4-pregnene-17 α ,21-diol-3,20-dione 21-acetate.

Example 7

Employ the process of Example 5, substituting for the dimethylsulfoxide solvent 100 ml. of diethylformamide, to prepare $9\beta,11\beta$ -oxido-4-pregnene-17 α ,21-diol-3,20-dione 21-acetate.

Example 8

Stir a mixture of 3.82 g. 9α -bromo-4-androstene-11 β -ol-3,17-dione, 2.32 g. of potassium fluoride and 100 ml. of dimethylformamide at 90° C. for 8 hours. Pour the reaction mixture into about 1.5 ml. of ice water with continued stirring. Separate the crude $9\beta,11\beta$ -oxido-4-androstene-3,17-dione by filtration and purify by recrystallization from acetone-petroleum ether.

Example 9

Employ the process of Example 9, substituting for the dimethylformamide solvent 100 ml. of diethylacetamide, to prepare $9\beta,11\beta$ -oxido-4-androstene-3,17-dione.

Example 10

Employ the process of Example 9, substituting for the dimethylformamide solvent 100 ml. of N-methyl- α -pyrrolidone, to prepare $9\beta,11\beta$ -oxido-4-androstene-3,17-dione.

Example 11

Mix 4.45 g. of 9 α -bromo-4-pregnene-11 β ,17 α ,21-triol-3,20-dione, 2.32 g. of potassium fluoride and 100 ml. of N-ethyl- α -pyrrolidone. Stir the mixture at 90° C. for about 6 hours. Pour the reaction mixture into about 1.5 l. of ice water and separate the crude $9\beta,11\beta$ -oxido-4-pregnene-17 α ,21-diol-3,20-dione by filtration. Purify by recrystallization from acetone.

Example 12

Employ the process of Example 11, substituting for the N-ethyl- α -pyrrolidone solvent 100 ml. of N-methyl- α -piperidone, to prepare $9\beta,11\beta$ -oxido-4-pregnene-17 α ,21-diol-3,20-dione.

Example 13

Employ the process of Example 12, substituting for the N-ethyl- α -pyrrolidone solvent 100 ml. of N-ethyl- α -piperidone, to prepare $9\beta,11\beta$ -oxido-4-pregnene-17 α ,21-diol-3,20-dione.

Example 14

Stir at 75° C. for about 8 hours a mixture of 3.0 g. of 16β -methyl-9 α -bromo-1,4-pregnadiene-11 β ,17 α ,21-triol-3,20-dione, 1.32 g. of potassium fluoride and 60 ml. of dimethylsulfoxide. Pour the reaction mixture into about 1.5 ml. of ice water and separate the crude 16β -methyl- $9\beta,11\beta$ -oxido-1,4-pregnadiene-17 α ,21-diol-3,20-dione by filtration. Purify the crude product by recrystallization from acetone-ether.

Example 15

Employ the process of Example 14, substituting for the dimethylsulfoxide solvent 100 ml. of tetrahydrothiophene sulfoxide, to prepare 16β -methyl- $9\beta,11\beta$ -oxido-1,4-pregnadiene-17 α ,21-diol-3,20-dione.

The subject matter which applicant regards as his invention is particularly pointed out and distinctly claimed as follows:

- 20 1. The process for the conversion of a 9α -bromo-11 β -hydroxy steroid into the corresponding $9\beta,11\beta$ -epoxide which comprises treating said 9α -bromo-11 β -hydroxy steroid with at least 2 moles of potassium fluoride per mole of steroid in at least five liters per mole of steroid of a solvent selected from the group consisting of S,S-di-lower alkyl sulfoxides wherein the lower alkyl moiety contains from 1 to 4 carbon atoms, cyclo-lower alkyl sulfoxides wherein the cyclo-lower alkyl moiety contains from 4 to 5 carbon atoms, N,N-di-lower alkyl formamides and N,N-di-lower alkyl acetamides wherein the lower-alkyl moiety contains from 1 to 2 carbon atoms, and N-lower alkyl- α -pyrrolidones and N-lower alkyl- α -piperidones wherein the lower alkyl moiety contains from 1 to 2 carbon atoms at a temperature of about 25 to 100° C.
- 25 2. The process of claim 1 wherein the solvent is dimethylsulfoxide.
- 30 3. The process of claim 1 wherein the solvent is diethylsulfoxide.
- 35 4. The process of claim 1 wherein the solvent is diethylformamide.
- 40 5. The process of claim 1 wherein the solvent is diethylacetamide.
- 45 6. The process of claim 1 wherein the solvent is diethylpyrrolidone.
- 50 7. The process of claim 1 wherein the solvent is diethylacetamide.
- 55 8. The process of claim 1 wherein the solvent is N-methyl- α -pyrrolidone.
- 60 9. The process of claim 1 wherein the solvent is N-methyl- α -piperidone.
- 65 10. The process of claim 1 wherein the solvent is tetrahydrothiophene sulfoxide.
- 70 11. The process for the conversion of a 9α -bromo-11 β -hydroxy steroid into the corresponding $9\beta,11\beta$ -epoxide which comprises treating said 9α -bromo-11 β -hydroxy steroid with about 4 moles of potassium fluoride per mole of steroid in about 10 liters per mole of steroid of a solvent selected from the group consisting of S,S-di-lower alkyl sulfoxides wherein the lower alkyl moiety contains from 1 to 4 carbon atoms, cyclo-lower alkyl sulfoxides wherein the cyclo-lower alkyl moiety contains from 4 to 5 carbon atoms, N,N-di-lower alkyl formamides and N,N-di-lower alkyl acetamides wherein the lower alkyl moiety contains from 1 to 2 carbon atoms, and N-lower alkyl- α -pyrrolidones and N-lower alkyl- α -piperidones wherein the lower alkyl moiety contains from 1 to 2 carbon atoms at a temperature of from 75 to 90° C.
- 75 12. The process of claim 11 wherein the solvent is dimethylsulfoxide.
- 80 13. The process of claim 11 wherein the solvent is diethylsulfoxide.
- 85 14. The process of claim 11 wherein the solvent is diethylformamide.
- 90 15. The process of claim 11 wherein the solvent is diethylacetamide.

16. The process of claim 11 wherein the solvent is dimethylacetamide.

17. The process of claim 11 wherein the solvent is diethylacetamide.

18. The process of claim 11 wherein the solvent is N-methyl- α -pyrrolidone.

19. The process of claim 11 wherein the solvent is N-methyl- α -piperidone.

20. The process of claim 11 wherein the solvent is tetrahydrothiophene sulfoxide.
